WELL CLEANING DEVICE

Victor F. Ehrgeit, Los Angeles, Calif., assignor to
John Grant, Los Angeles, Calif.

Application February 12, 1935, Serial No. 6,157

19 Claims. (Cl. 166—19)

This invention has to do generally with well cleaning devices and is more particularly concerned with such devices wherein there is provided a low-pressure-holding or charge-receiving chamber with a normally closed inlet adapted to be opened at predetermined points in the well whereby the well fluid, under relatively high pressure, charges that chamber with sand or other foreign matter adjacent the inlet, or sets up such pressure actions or high velocity fluid-movements as to dislodge foreign matter which may be offering obstruction to free passage of fluid through fissures in the formation or perforations in the well casing.

While the invention is here described in connection with a device having a single-charge low-pressure chamber adapted to be emptied after each charging and after the tool has been lifted from the well, it will be understood the illustrated inlet valve for said chamber and the valve-control mechanism may be applied with advantage to the inlet of any type of low pressure chamber, irrespective of the manner in which the charged chamber is subsequently emptied or prepared for re-charge, and therefore the showing of the invention as embodied in connection with a particular type of chamber is not to be considered as limitative on such broader aspects of the invention.

The device will here be described as utilized in the cleaning of casing perforations, to which use it is particularly well adapted, but this particularized description is not to be considered as in any way limitative on the adaptability of the device for other cleaning operations.

It is highly important that the inlet to the low pressure chamber be kept tightly closed until the cleaner has reached the predetermined zone of operation and yet, in spite of that tight closure and in spite of the usually high fluid pressure in that zone, the inlet must be capable of practically instantaneous full-opening, under the control of the operator, after reaching that zone.

Therefore it is among the general objects of the invention to provide a cleaner which shall have the above desirable features, as well as others which may be pointed out to better advantage in connection with the detailed description to follow.

It may here be pointed out, however, that the present invention contemplates a cleaner having an inlet valve which, in effect, is adapted to open downwardly against the pressure of the well-fluid, with an associated balancing arrangement whereby the effective pressure area exposed to that

well fluid is reduced to an extent which renders the valve readily opened by the application of relatively moderate forces when the zone of operation is reached. Or, considering the invention in its broader aspects, the valve may be fully balanced as regards the fluid pressure applied thereto with a spring depended upon to hold it closed. In this event the requisite unseating force is only that required to overcome the spring. However, it is preferred that there be effective pressure-area exposed to the well fluid, so, as the tool is lowered to increased depth in the fluid with the resulting higher pressures tending to increase the danger of leakage at the valve, such higher pressures coincidentally become effective to seat the valve tighter and thereby offset the increased leakage tendency.

In the preferred embodiment of the invention I also provide means whereby, in spite of the fact that the inlet closure is below the charge-receiving chamber, the effects of leakage into the low-pressure side of the balancing cylinder are reduced to a minimum and whereby, immediately after the closure is moved from its seat, the low pressure chamber of the balancing cylinder is opened to well pressure and the entire cylinder is exposed to balanced fluid pressure so there is no tendency for the well pressure or any air which might otherwise have been trapped in said low pressure chamber, to reclose the valve.

Other objects and features of the invention will become apparent from the consideration of the detailed description to follow.

In the drawings:

Fig. 1 is a side elevation of a cleaner embodying my invention;

Fig. 2 is an enlarged section on line 2—2 of Fig. 1;

Fig. 3 is an enlarged section on line 3—3 of Fig. 1, the showing of the valve at the bottom of Fig. 2 being here repeated at the top of Fig. 3 in order better to relate the parts;

Fig. 4 is an enlarged section on line 4—4 of Fig. 1;

Fig. 5 is a section on line 5—5 of Fig. 3;

Fig. 6 is a view similar to Fig. 3 but showing the valve parts in changed position; and

Fig. 7 is a view similar to Fig. 6 but showing the valve parts in still another position.

As has been previously stated, the cleaning device is particularly well adapted, but not limited, to the dislodgment of foreign matter from the perforations of well casing, and therefore I have illustrated the device as positioned within such a perforated casing or screen A having any suit-

55

able type of perforations, here conventionally illustrated at B.

Body member C of the cleaning device is here shown as made up of a plurality of sections coupled end-to-end, though it will be understood that the showing of such sectional characteristics is not to be considered as limitative on the invention.

Threadably connected body or casing sections 10 are indicated at 10, 11 and 12; section 10 (Fig. 2) serving as a head or top closure for the charge-receiving or low-pressure chamber D which is annularly defined by those sections. Attachment section 13 is threadably connected to section 10 15 and serves as means whereby the body member may be attached to a suspension element—cable 14, for instance. Section 11, here shown as longitudinally contracted, may be of any desirable length and may, itself, be sectional. A forty foot 20 length gives chamber D a capacity ample for most operations.

Section 10 has a reduced axial bore 15 from which extends a transverse passageway 16 controlled by a spring-closed, outwardly-opening relief valve generally indicated at 17. The function of this valve is merely to relieve high pressure in the charge-receiving chamber as the tool is raised into zones of lower pressure. To facilitate unloading of chamber D, I preferably provide inwardly-opening, spring-closed dump relief valve 18. This valve is fully described and claimed in the copending application of W. C. Erwin et al. on Well bailers, filed April 22, 1933, Ser. No. 667,439 wherein the valve showing is substantially identical with the present showing. It will suffice here to state that screw plug 19 normally closes passageway 20. When chamber D is to be unloaded, plug 19 is moved and passageway 20 is then adapted to put that chamber into communication with the atmosphere when the negative pressure therein (as created by the dumping of the fluid) is of a value allowing spring-closed valve 18 to open under atmospheric pressure.

Screwed into the lower end of section 12 is a bushing 21 whose bore 22 may be considered as the inlet opening of chamber D, the bushing presenting an upwardly facing seat 23 to take a foot-valve 24. Bar 25 acts as a stop to limit the upward movement of valve 24. Section 12 is also provided with a removable dump-door 26, the construction and mounting thereof being the same as that illustrated and more fully described in the copending application Ser. No. 667,439, which also contains claims to these features. The door 55 is opened by loosening screws 27 (which normally press the door inwardly to compress gasket 28 and provide a fluid-tight seal) and then sliding the door transversely to clear lugs 29 from overhanging lips 30, which latter define way 31.

Coupled to section 12 by bushing 21 is a section 32 which may be considered as a part of body C or as a depending extension thereof. Valve seat 33, of the inlet valve assembly indicated generally at V, is provided at the lower end of bushing 21 around inlet port 22. A sleeve, generally indicated at 34, is made up of threadably connected sections 35 and 36, sleeve section 35 being longitudinally slidable on body section 32. Coupled to sleeve section 36 at 37 is a tubular extension 38 having lateral intake ports 39 which open to intake duct G (made up of the communicating bores of sections 38, 36 and 35, and the vertical passageways 40 through nut 41 which is screwed into the lower end of section 75 32) which duct leads to valve assembly V and,

when the valve is opened, to inlet 22. A shoe or guiding nose 42 on tube 38 closes the lower end of duct G and is preferably fluted at 43 so well-fluid may pass with minimum interference between the well casing and shoe as the tool is raised or lowered, to obvious advantage.

For controlling or effecting the opening of valve V, I provide a member 44 mounted for movement longitudinally with respect to the body C and engageable with well casing A, plus an operative connection between that member and valve V whereby movement of the member with relation to the body sets up or controls movement of the valve. In this particular case, member 44 is carried on sleeve section 36, and since the latter is telescopically arranged with respect to body section 32, it will be seen that the described capacity for relative movement between the body and member arises from the provision of a slip-joint between the body and an element other than member 44, per se, though the invention, considered in its broader aspects, contemplates the mounting of the member directly on but slidable with respect to the body.

Since I have chosen here to show the invention as particularly applied to a device for cleaning casing perforations wherein it becomes preferable to provide a packer for localizing the cleaning effect therebelow and particularly at intake ports 39, I have indicated the utilization of member 44 both as the element which is operatively connected to the valve for controlling or effecting the opening thereof, and as a packer. However, it will be understood that the invention, considered in its broader aspects, is not limited to use of member 44 as a packer, for in certain cleaning operations a packer is not essential.

With member 44 in the form of a packer positioned above intake ports 39 (whereby the zone of operation is isolated from the fluid-column in the well casing above the member so the effect of a sudden charging of chamber D is more or less localized about the intake ports) it will be seen that the packer obstructs the space between the cleaner and well casing and, when the packer is moved upwardly, the fluid column thereabove tends to expand it radially into tighter frictional engagement with the well casing.

Accordingly, in raising or lowering the cleaner it is desirable to by-pass the fluid around the packer, but since I have here shown duct G serving both as an intake passage leading to the inlet valve and as a part of the by-passage, it becomes desirable that when the duct is used for intake purposes the by-pass ports opening to that duct above the packer be closed off. This prevents fluid from being drawn inwardly through the by-pass ports from outside the isolated intake zone, which otherwise would minimize the localizing effect within that zone when chamber D is suddenly opened to receive a charge.

Therefore, in the preferred embodiment of my invention, I have shown means operable to close the by-pass ports and have given member 44 the additional function of operating that closure, as will be described. It is to be noted, however, that the following described particularities of member 44 and the by-passage control are not to be considered as limitative on the broader aspects of the invention.

Member 44 is here illustrated as a packer of a type well known in the art, consisting of an upwardly opening cup 45 of rubber or other suitable resilient material held against sleeve-shoulder 46 by cup-member 47, the latter being held,

in turn, by coupling 37. Cup 45 may be reinforced by spring wire 48. Hereinafter member 44 will be referred to as a packer, but this reference is subject to the reservations noted above.

5 Valve member 50 is made up of a plug or closure portion 51 having conical face 52 adapted to engage seat 33, and a depending skirt portion 53 which, as will appear, serves as a balancing cylinder. The upper part of the skirt or cylinder 10 portion is fluted at 54, while pins 55 project from the lower part, the pins extending through longitudinally extending slots 56 and 57 in body-section 32 and sleeve-section 35 respectively. When plug 51 is seated (Fig. 3) pins 55 are near 15 the top and bottom of slots 56 and 57, respectively. A protector sleeve 57a is welded or otherwise suitably secured to section 35 to cover slots 51.

Secured to and extending upwardly from nut 20 41 is a stem 58 carrying a barrier or piston 59 which is entered in the bore of cylinder 53, dividing that bore into what may be termed low-pressure and high-pressure balancing chambers 60 and 61, respectively. Piston 59 is fitted with packing 25 in the form of a downwardly-opening cup-ring 62, whereby fluid pressure from below is adapted to force said ring into sealing engagement with the cylinder wall and thus prevent leakage from high-pressure to low-pressure 30 chambers.

Now the invention broadly contemplates situations wherein the exposed faces of valve parts are effective in varying degrees to take well-pressure in a manner tending to hold the valve closed. 35 Likewise, the arrangement has advantageous features which may be taken advantage of whether or not there be an opening (as shown) through plug 51. Therefore, the showing and the following description of certain relative dimensional and 40 structural particularities are not to be considered as limitative on the broader aspects of the invention, though their provision is preferred since they give added advantage.

Compression spring 63 is interposed between 45 nut 41 and a thrust washer 64 on the underside of cylinder 53, side-ports 65 permitting well-fluid to enter chamber 61. Port 66 opens through the top of plug 51 to place chambers D and 60 in communication when the inlet valve is closed, the 50 purpose of this provision being made apparent later, though, as said above, the invention, considered broadly, is not limited to a ported plug. However, where the plug is ported at the top, it will be seen that member 50 may be considered 55 as hollow or tubular throughout its length, with piston 59 adapted to slide through the member-bore.

Depending from nut 41 is stem 67 carrying the tubular closure 68, the upper end of which is 60 below by-pass port 69 in sleeve-section 36 when the parts are in the position of Fig. 3 where the cleaner is shown in the condition in which it is lowered to take a charge. Well fluid may thus by-pass the packer through ports 39, duct G and 65 ports 69.

As the cleaner is initially lowered, packer 44 engages the well casing in a manner tending to retard downward movement of sleeve 34, it following that the telescopic joint between body and 70 sleeve is relatively contracted, the weight of the body acting through member 50 and pins 55 against shoulders 70 at the lower ends of sleeve-slots 57 to force down sleeve 34 and packer 44. Or, due to the resistance to downward movement 75 offered by the packer and sleeve, it may be con-

sidered that these members serve initially to hold the inlet valve closed. In the event the body and sleeve are not initially telescoped as above, or if for any reason they are partially relatively extended before the fluid is reached, spring 63 5 serves to hold plug 51 seated on face 33.

Now, to be effective as a closure, plug 51 must be of greater diameter than inlet port 22. If the underface of a plug of that diameter were fully exposed to well-fluid, the opening means would 10 have to pull the valve closure down against fluid pressure directed against an area equal to the cross-sectional area of the plug, and, particularly where the tool is at great depth in the well-fluid, 15 the resistance to valve-opening might thus be beyond the capacity of available opening forces. By interposing a stationary barrier (piston 59) in the bore of cylinder 53, much of this up-bearing 20 fluid pressure is taken from the closure or, expressed otherwise, the effective pressure area on the closure is greatly reduced. In fact, by properly proportioning the diameter of the plug and piston, the closure may be completely balanced so the only means holding it closed is 25 spring 63. While such proportioning lies within the scope of my invention, considered broadly, it is preferable that the fluid pressure be effective to hold the plug in closing position to a certain degree, at least, so as greater depths are reached 30 the increased tendency for fluid to leak through the valve is offset by the tighter closing of the valve.

In the illustrated embodiment of the invention, the effective pressure area (Fig. 3 above member 50) is represented by the cross-sectional area of 35 a ring having an outside diameter a (the diameter of plug 51) and an inside diameter b (the diameter of chamber 60). With the effective pressure area thus reduced, it lies well within the power 40 of a very simple operating means to pull the closure from its seat.

Chamber 60 being in communication through port 66 with the large-capacity chamber D, the effect of leakage from chamber 61 past piston 59 45 into chamber 60 becomes a negligible factor. This intercommunication between chambers prevents the trapping of leakage-fluid in chamber 60 which otherwise would offer resistance to or prevent relative contractive movement of the piston and cylinder and would upset the substantial balance of the closure.

When the cleaner reaches the zone of operation, descent of the tool is checked and limited with withdrawal movement is imparted thereto by reeling-in cable 14. Since packer 44 resists upward movement, due to its frictional engagement with casing A, body section 32 moves upwardly with relation to sleeve 34, the valve and all its associated elements remaining in the positions shown in Fig. 3 until pins 55 engage shoulders 71 defining the upper ends of sleeve-slots 57. During this movement, however, sleeve closure 68 is drawn upwardly by stem 67 to a position blanking by-pass port 69. With pins 55 engaging shoulders 71, and said pins and member 50 thus held against further upward movement, continued upward movement of the body draws seat 33 away from plug 51, thus opening inlet 22 (Fig. 6).

Well-fluid is then free to rush through ports 39, duct G and inlet 22 into low pressure chamber D. The fluid carrying with it foreign matter (which is to be "bailed"), it being noted that by-pass ports 69 remain closed at this time by the blanking effect of the lower extent of sleeve 68. Where the device is used as a perforation cleaner 75

the in-rush sets up such movement in the well-fluid surrounding the tool below the packer as to dislodge "slugs" of foreign matter in the perforations of the well casing. The slugs (which 5 are sometimes broken up by the fluid action and sometimes are removed intact) usually, though not necessarily, are carried into chamber D along with the in-rushing fluid.

Ball-valve 24 rises, of course, during the inrush 10 of the fluid and thereafter settles to seat 23 to act as a foot-valve. Continued elevation of the body member moves the parts to the positions of Fig. 7 wherein it will be noted that sleeve 68 has been raised to a position uncovering by-pass ports 69 15 so, as the cleaner is subsequently withdrawn, well-fluid may again by-pass around the packer. During final withdrawal movement of the body member, pins 57 continue to engage shoulders 71 and thus serve, in effect, to drag sleeve 34 and 20 packer 44 upwardly through the well-casing.

It is to be noted that immediately upon the parting of valve faces 33, 52, chamber 60 is 25 opened to well-pressure, so member 50 becomes fully balanced and further opening movement of the valve is accomplished in the most advantageous manner.

While I have illustrated and described a preferred embodiment of my invention, it will be understood this is to be considered as illustrative 30 of and not limitative on the broader aspects of the invention, for various changes in design, structure and arrangement may be made without departing from the spirit and scope of the appended claims. For instance, it will be recognized that while, in the illustrated embodiment 35 of the invention, the valve movement from closed to open position is downward with respect to the overlying low pressure chamber D (whereby it follows that, when valve V is closed, the upper end 40 of closure 50 is exposed to that chamber, and the lower end of the closure is exposed to well-fluid) more fundamentally this valve movement may be considered as away from the low-pressure chamber whether that chamber be above or below the 45 valve, and therefore references in certain of the appended claims as to particular directions of movement or to particular vertically defined locations or exposures of elements, are merely for the purpose of relating their movements, positions or exposures and are not otherwise to be construed as limitative on those claims.

I claim:

1. In a well-cleaning device, a body having a 55 low-pressure chamber with an inlet, a movable closure for the inlet, a cylinder carried by the closure, and a piston carried by the body and entered in the cylinder bore.

2. In a well-cleaning device, a body having a 60 low-pressure chamber with an inlet, a movable closure for the inlet, a cylinder carried by the closure, and a piston stationarily carried by the body and entered in the cylinder bore.

3. In a well-cleaning device, a body having a 65 low-pressure chamber with an inlet, a downwardly opening closure for the inlet, a cylinder carried by the closure, and a piston carried by the body and entered in the cylinder bore.

4. In a well-cleaning device, a body having a 70 low-pressure chamber with an inlet, a member movable with respect to the body member and including a closure for the inlet and a cylinder; and a piston carried by the body and entered in the cylinder bore, the effective cross-sectional area of the closure being greater than the cross-sectional area of the cylinder bore.

5. In a well-cleaning device, a body having a low-pressure chamber with an inlet, a movable closure for the inlet, a cylinder carried by the closure, a piston carried by the body and entered in the cylinder bore, and means for moving the cylinder over the piston to draw the closure from the inlet.

6. In a well-cleaning device, a body having a low-pressure chamber with an inlet, a downwardly opening closure for the inlet, a cylinder carried 10 by the closure and a piston carried by the body and entered in the cylinder bore at a point spaced below the top thereof, the lower end of the cylinder being adapted to be exposed to well-fluid.

7. In a well-cleaning device, a body having a 15 low-pressure chamber with an inlet, a downwardly opening closure for the inlet, a cylinder carried by the closure and a piston stationarily carried by the body and entered in the cylinder bore at a point spaced below the top thereof, the lower 20 end of the cylinder being adapted to be exposed to well-fluid.

8. In a well-cleaning device, a body having a low-pressure chamber with an inlet, a downwardly opening closure for the inlet, a cylinder carried 25 by the closure, a piston carried by the body and entered in the cylinder bore at a point spaced below the top thereof, the lower end of the cylinder being adapted to be exposed to well-fluid, and means for moving the cylinder relatively 30 downwardly over the piston.

9. In a well-cleaning device, a body having a low-pressure chamber with an inlet, a downwardly opening closure for the inlet, a cylinder carried by the 35 body and entered in the cylinder bore at a point spaced below the top thereof, the lower end of the cylinder being adapted to be exposed to well-fluid, there being a passageway through said closure adapted to put into communication the low-pressure chamber and the cylinder bore above the piston when the closure is in closing position.

10. In a well-cleaning device, a body having a low-pressure chamber with an inlet therefor, a downwardly opening closure for the inlet and embodying a tubular member, a piston carried by the 45 body and entered in the member-bore, the bore of the member above the piston normally communicating with the low-pressure chamber and the lower end of the tubular member being 50 adapted to be exposed to well-pressure.

11. In a well-cleaning device, a body having a low-pressure chamber with an inlet therefor, a downwardly opening closure for the inlet and embodying a tubular member, a piston stationarily 55 carried by the body and entered in the member-bore, the bore of the member above the piston normally communicating with the low-pressure chamber and the lower end of the tubular member being 60 adapted to be exposed to well-pressure.

12. In a well-cleaning device, a body having a low-pressure chamber with an inlet therefor, a closure for the inlet, a cooperating piston and cylinder below the chamber and associated with the closure for substantially balancing the effect 65 of fluid pressure directed, in effect, against the closure, there being a low-pressure chamber within the cylinder at one side of the piston, and there being a passageway putting said low-pressure chambers into communication when the inlet 70 is closed.

13. In a well-cleaning device, a body having a low-pressure chamber with an inlet, a member shiftably mounted on the body, a vertically movable closure for the inlet normally held in closing 75

position, a cylinder carried by the closure, a piston carried by the body and entered in the cylinder bore, and an operative connection between said member and closure whereby a relative shift of the body and member moves said closure vertically from the inlet.

14. In a well-cleaning device having an external packer and embodying a body member having a low-pressure chamber with an inlet, there being a by-passage around the packer, a member shiftably mounted on the body, a movable closure for the inlet normally held in closing position, a cylinder carried by the closure, a piston carried by the body and entered in the cylinder bore, a by-pass closure on one of the members and normally out of closing position, and an operative connection between the shiftable member and inlet closure, all in a manner whereby relative shifting of the members sequentially moves the by-pass closure into closing position and moves the inlet closure from the inlet.

15. In a well-cleaning device having an external packer and embodying a body member having a low-pressure chamber with an inlet, there being a by-passage around the packer, a member shiftably mounted on the body, a movable closure for the inlet normally held in closing position, a cylinder carried by the closure, a piston carried by the body and entered in the cylinder bore, a by-pass closure on one of the members and normally out of closing position, and an operative connection between the shiftable member and inlet closure, all in a manner whereby relative shifting of the members sequentially moves the by-pass closure into closing position, moves the inlet closure from the inlet, and moves the by-pass closure from closing position.

16. In a well-cleaning device adapted to be lowered through a well-casing, a body member having a low-pressure chamber with an inlet, a member shiftably mounted on the body and adapted to engage the casing whereby withdrawal movement of the body relatively moves said mem-

ber, a vertically movable closure for the inlet normally held in closing position, a cylinder carried by the closure, a piston carried by the body and entered in the cylinder bore, and an operative connection between said shiftable member and closure whereby relative movement of the members as set up by withdrawal movement of the body moves said closure vertically from the inlet.

17. In a well-cleaning device adapted to be lowered through a well-casing, a body member having a low-pressure chamber with an inlet, a member shiftably mounted on the body and adapted to engage the casing whereby withdrawal movement of the body relatively moves said members, a vertically movable closure for the inlet normally held in closing position, a cylinder carried by the closure, a piston carried by the body and entered in the cylinder bore, and a pin and slot connection between said shiftable member and closure whereby relative movement of the members as set up by withdrawal movement of the body moves said closure vertically from the inlet.

18. A valve for the inlet of a chamber, embodying a piston held in axial alignment with the inlet, a closure for the inlet, and a cylinder carried by the closure and taking the piston within its bore, said closure being movable over the piston towards and away from said inlet, there being a passageway through the closure from the cylinder at one side of the piston and opening to said inlet when the closure is in closing position.

19. A valve for the inlet of a chamber, embodying a piston held in axial alignment with the inlet, a closure for the inlet, and a cylinder carried by the closure and taking the piston within its bore, said closure being movable over the piston towards and away from said inlet, there being a passageway through the closure from the cylinder at one side of the piston and opening to said chamber when the closure is in closing position.

VICTOR F. EHREGOTT.
